(57) **CLAIM**

I claim the ornamental design for a bracelet and anchor set, as shown and described.

DESCRIPTION

FIG. 1 is a perspective view of a bracelet and anchor set; FIG. 2 is a side view thereof;

FIG. 3 is another side view thereof;

FIG. 4 is a front view thereof;

FIG. 5 is a back view thereof;

FIG. 6 is a top view thereof;

FIG. 7 is a bottom view thereof;

FIG. 8 is a perspective view thereof, shown in a configuration of use;

FIG. 9 is another perspective view thereof, shown in a configuration of use; and,

FIG. 10 is another perspective view thereof, shown in a configuration of use.

Broken lines illustrate environmental features and form no part of the claimed design.
